(57) **CLAIM**

The ornamental design for a phone case kick stand, as shown and described.

DESCRIPTION

FIG. 1 is a bottom rear perspective view of a phone case kick stand, showing my new design;

FIG. 2 is a rear elevation view thereof;

FIG. 3 is a front elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a bottom rear perspective view of the phone case kick stand, shown in a collapsed condition.

The evenly sized dash-dash broken lines depict portions of the phone case kick stand that form no part of the claimed design, while the alternately sized dash-dot broken lines shown in the drawings depict the bounds of the phone case kick stand that form no part of the claimed design.
